(57) **CLAIM**

The ornamental design for an old world Tuscan one-piece molded panel, as shown and described.

DESCRIPTION

FIG. 1 is a front view of a one-piece molded panel for the wall of a tub or shower enclosure showing our old world Tuscan design;

FIG. 2 is a cross-sectional view taken along line 2-2 of FIG. 1; FIG. 3 is a cross-sectional view taken along line 3-3 of FIG. 1; FIG. 4 is an enlarged view of the diamond element shown in the design in FIG. 1; and,

FIG. 5 is an enlarged cross-sectional view of the diamond element taken along line 5-5 of FIG. 4.

The right side, left side, top, bottom and back of the one-piece molded panel are flat and unadorned and do not form a part of the claimed design.

The claimed design is shown broken away on the left and right side and in the vertical dimension to indicate unclaimed width and height.
